HEATER CABINET

Judkins E. Wilkinson, Birmingham, Ala., assignor to Atlanta Stove Works, Inc., a corporation of Georgia

Filed Jan. 2, 1959, Ser. No. 54,018

Term of patent 14 years

(Cl. D81—19)

Fig. 1 is a front elevational view of a heater cabinet showing my new design;

Fig. 2 is a fragmentary sectional view, taken along the line 2—2 of Fig. 1;

Fig. 3 is a side elevational view of the cabinet, the opposite side thereof being similar except that the door shown in Fig. 3 is omitted from said opposite side; and

Fig. 4 is a perspective view showing in detail the lower grill in Fig. 1.

The dominant features of the design reside in the portions shown in full lines.

I claim:

The ornamental design for a heater cabinet, as shown and described.
